UNITED STATES PATENT OFFICE.

JOSEPH PREATKA, OF NEW YORK, N. Y.

FLYING-MACHINE.

1,256,986.

Specification of Letters Patent.

Patented May 21, 1918.

Application filed March 30, 1918. Serial No. 225,686.

To all whom it may concern:

Be it known that I, JOSEPH PREATKA, a subject of the King of Hungary, and a resident of the city of New York, in the county of New York and State of New York, have invented certain new and useful Improvements in Flying-Machines, of which the following is a specification.

The present invention relates to flying machines, and more particularly to that type in which the means of sustentation and propulsion consists of beating wings.

The main object of the invention is to provide a machine of the character specified with at least two pairs of wings, the wings of one pair always working in opposite direction in relation to the wings of the other pair, whereby the safety of the machine is greatly increased.

Another object of the invention is to provide a device which is light in weight, simple in construction, comparatively inexpensive to manufacture, strong and durable.

A further object of the invention is to so mount the beating planes on the frame of the machine that, in case of accident, at least one pair thereof will act as planes to permit a gradual descent by gliding.

With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:

Figure 1 is a side elevation of a flying machine constructed in accordance with the present invention; Fig. 2 is a top plan view thereof; Fig. 3 is a front elevation of the same; Fig. 4 is a section taken on line 4—4 of Fig. 3; and Fig. 5 is a portion of a section taken on line 5—5 of Fig. 4.

In the drawings, the numeral 10 indicates the car or body of a flying machine, resembling that of a bird, having long streamlines, so as to present as little resistance to the air as possible. This body is mounted upon front wheels 11 and rear wheels 12, for the well-known purpose. The front wheels 11 are mounted upon a shaft 13, and are connected therewith by clutches 14 of any suitable construction, suitable clutch engaging and disengaging means 15 being provided.

From the body or car of the machine rises, above the shaft 13, a frame 16, including side pieces 17, that are united by a front piece 18 and a rear piece 19, thus constituting a guide for a head 20, which is reciprocably mounted in the said frame. The head is reciprocated from the shaft 13 in any suitable manner, for instance the said shaft may be provided with a crank 21, in engagement with the lower end of a connecting rod 22, the upper end of which is pivoted to a pin 23 on the said head. The connecting rod is made of two sections 24 and 25, for a purpose hereinafter to be described. The connection between the two sections of the rod is made of a pin 26, which may be engaged with or disengaged from the said two sections, at will.

Rotation is imparted to the shaft 13 from a motor (not shown) in the car or body of the machine, power being transmitted from said motor to the said shaft in any suitable manner; for instance to the shaft is fixedly attached a bevel gear 27, in mesh with a similar gear 28, the shaft 29 of which is driven from the motor.

The means of sustentation and propulsion consists of two pairs of beating wings. One pair of these wings, denoted by the numeral 30, swings around a substantially horizontal pivot 31 that is in parallel relation to the longitudinal axis of the car or body of the flying machine, while the other pair of wings, indicated at 32, swings around a substantially horizontal pivot 33, that extends transversely of the said car or body. The wings 30 are disposed above the wings 32 at a distance that they do not interfere with the operation thereof. The wings 30 are rigidly attached to arms 34, through the in-

2
ner ends of which extends the pivot 31, the latter being carried by the frame 16. The arms 34 are provided with longitudinal slots 35, and through these slots extend lugs 36, 5 that are carried by the reciprocating head 20. The wings 32 are also rigidly attached to arms, denoted by the numeral 37, and through the inner ends of these arms extends the pivot 33, said last-named pivot being 10 carried by the reciprocating head 20. The arms 37 are provided with longitudinal slots 38, through which extend lugs 39, mounted upon brackets 40, that are secured by suitable means to the frame 16. The lugs 36, 15 above referred to, extend in parallel relation to the pivot 31, and the lugs 39 in parallel relation to the pivot 33.

The steering means or rudders of the machine are disposed at the tail-end of the car 20 or body 10, and comprises horizontal rudders 41 and a vertical rudder 42, which need no further detailed description, as they do not form part of the present invention.

The operation of this device is as follows:—If it is intended to let the machine run on the ground without actuating the sustentation and propulsion means thereof, the pin 26 is disengaged from the connecting rod 22 and the clutches 14 actuated so as to 25 connect the wheels 11 with the shaft 13. If now the motor of the machine is started, the said wheels will be turned in the proper direction to propel the machine on the ground. Obviously suitable steering means must be 30 provided for directing the course of the machine while on the ground.

When the two sections of the connecting rod are properly connected and the motor started, the machine will be propelled on the 40 ground and at the same time the sustentation and propulsion means actuated. The machine will then rise from the ground after the horizontal rudders 41 thereof are placed in proper position. The two pairs of wings 45 are actuated by the reciprocating head 20 in the following manner: The lugs 36, co-acting with the slots of the arms 34 of the wings 30, move up and down, thereby causing the said wings to swing around their 50 pivot 31; on the other hand, the pivot 33 of the wings 32 moves up and down, whereby the last-named wings are caused to swing around the said pivot by reason of the slots 38 being in engagement with the lugs 39 55 above mentioned. In this manner the wings 30 move always in a direction opposite to that of the wings 32, that is to say, when the wings 30 swing downward, the wings 32 are caused to swing upward, and vice versa. 60 In this manner the safety of the machine is greatly increased, there being always one pair of wings which causes a pressure of air downward. The two pairs of wings do not interfere with each other in their operation, 65 as one pair of the same swings around a

pivot that is disposed in parallel relation to the longitudinal axis of the car or body, while the pivot of the other pair is disposed transversely thereto.

By reason of the fact that the wings operate in opposite directions, one pair of the same will always act as planes to permit a gradual descent by gliding in case the motor gets out of order.

It is to be observed that, when in the air, 70 the wheels 11 may be caused to come to a standstill by disengaging the clutch members thereon from the clutch members co-operating therewith and fixed to the shaft 13.

From the foregoing it appears that the 80 machine is very simple in construction, comparatively inexpensive to manufacture, and may be very light in weight as the frame 16 and the head 20 may be made of either very light metal or wood. 85

What I claim is:—

1. In a flying machine, the combination with a car, of a frame rising therefrom, a head reciprocably mounted in said frame, a pair of wings pivoted to said frame and operatively connected with said head, and a pair of wings pivoted to said head and operatively connected with said frame. 90

2. In a flying machine, the combination with a car, of a frame rising therefrom, a head reciprocably mounted in said frame, a pair of wings pivoted to said frame provided with arms having longitudinal slots, lugs on said head seated in said slots, a pair of wings pivoted to said head provided with 100 arms having longitudinal slots, and lugs fastened to said frame and seated in the slots of said last-named arms.

3. In a flying machine, the combination with a car, of a frame rising therefrom, two 105 pairs of wings mounted upon said frame, and means for causing the wings of one pair to swing continuously in a direction opposite to those of the other pair, one pair of said wings swinging on pivots disposed parallel to the longitudinal axis of said car and the other pair on pivots at right angles to said first-named pivots. 110

4. In a flying machine, the combination with a car, of a frame rising therefrom, a 115 head reciprocably mounted in said frame, a pair of wings pivoted to said frame and operatively connected with said head, and a pair of wings pivoted to said head and operatively connected with said frame, the 120 pivots of one pair of said wings being disposed in parallel relation to the longitudinal axis of the car and the pivots of the other pair of wings at right angles to said first-named pivots. 125

5. In a flying machine, the combination with a car, of a frame rising therefrom, a head reciprocably mounted in said frame, a pair of wings pivoted to said frame provided with arms having longitudinal slots, 130

lugs on said head seated in said slots, a pair of wings pivoted to said head provided with arms having longitudinal slots, and lugs fastened to said frame and seated in the 5 slots of said last-named arms, the pivots of one pair of said wings being disposed in par-

allel relation to the longitudinal axis of the car and the pivots of the other pair of wings at right angles to said first-named pivots.

Signed at New York, in the county of 10
New York and State of New York.

JOSEPH PREATKA.
